SHAKE MECHANISM

Application filed August 24, 1928. Serial No. 301,865.

This invention relates to shake mechanisms and particularly to mechanisms of that class having means whereby the amplitude of the vibrations produced by the mechanism may be varied while the machine is in operation. The invention is designed specially for use in connection with paper-making machines of the Fourdrinier type, and for imparting to the travelling wire upon which the web of paper is formed a very rapid lateral vibratory motion, or shake; but the mechanism hereinafter described, and in which the present invention is embodied, is adapted for use in connection with machines of various sorts in which it is desired to impart to some element thereof a rapid vibratory motion of variable amplitude.

It has long been deemed desirable in the paper making industry to have a shake head so constructed that the amount of throw communicated to the Fourdrinier part of a paper machine could be adjusted to a nicety while the machine is in operation at full speed; for by that means the machine tender is enabled to observe the effects upon the pulp, while spreading itself upon the wire, of slight changes of adjustment, and thus to determine and obtain the precise amount of throw that is best suited for each batch of pulp. It has also been deemed desirable to provide means for varying the rapidity of the vibrations, that is the number of shakes per minute, as well as the amplitude thereof. This latter object is easily accomplished, as by the use of speed-varying cone gears; or by employing a variable speed electric motor for driving the main shaft of the shake mechanism.

It is likewise a comparatively easy matter to provide driving connections whereby the throw of the vibrations can be varied while the machinery is in operation; and in fact driving connections capable of accomplishing that result have heretofore been constructed and put into use.

But it has been found a matter of great difficulty to devise a mechanism of the above character that is capable of withstanding, for any considerable length of time and without serious deterioration, the great strain and

wear to which it is subjected by reason of the incessant shocks due to the rapidity of the vibrations and to the weight and consequent momentum of the parts that are vibrated.

It is well understood that reciprocatory movements, such as the oscillations of a rock-shaft, are the most difficult sort of movements the mechanic has to take care of; and it is also understood that the difficulties are magnified, and in much more than simple ratio, as the rapidity of vibration and the momentum of the parts to be vibrated are increased. Hence, in an apparatus designed for the accomplishment of the objects stated above—the vibrations being rapid and the momentum of the parts being great—the shocks are proportionately intense; and since all those shocks must pass through the adjusting devices, it has been found difficult to construct the same in such manner that they will not speedily break down, or their efficiency and precision be quickly impaired, by reason of the strain of the strong and incessant vibrations they must undergo.

Therefore the present invention has for one of its major objects to provide power-transmitting mechanism of the kind referred to, capable of ready adjustment while the machinery is running, and at the same time capable of withstanding, for a much longer period than any heretofore in use and without impairment as to its efficiency, the shock and wear of the vibrations.

In the accompanying drawings, in which the preferred embodiment of the invention is illustrated,

Fig. 1 shows the mechanism in elevation;

Fig. 2 is a top plan view of the part of the mechanism shown at the right hand side of Fig. 1;

Fig. 3 is a vertical section on line 3—3 of Fig. 2;

Fig. 4 is a vertical section on line 4—4 of Fig. 2;

Fig. 5 is a horizontal section on line 5—5 of Fig. 1;

Fig. 6 is a plan view of the rocker;

Fig. 7 is a vertical section on line 7—7 of Fig. 1;

Fig. 8 is a side elevation of the beam;

Fig. 9 is a vertical section on line 9—9 of Fig. 1; and

Figs. 10, 11 and 12 are detail views.

The main driving shaft 14 of the shake head 5 is supported in bearings 15, 15a, 15b, carried by standards 16, 16a, 16b respectively, all supported by base 17 (Figs. 2 and 3). Said main shaft 14 is driven by a variable speed electric motor 20 through pinion 21 and gear 10 22, the latter being fixed on said shaft 14.

The purpose of the mechanism as a whole, commonly called a "shake head", is to vibrate the shake frame of a paper machine (part of said frame being shown at 25, Fig. 1) from 15 power shaft 14 through connections which convert the rotatory motion of said shaft into very rapid vibrations, and which admit of the adjustment of amplitude or "throw" of said vibrations while the machine is in full 20 operation. Therefore the following detailed description will be occupied mainly with the construction of the parts whereby the above stated purpose is accomplished.

Power shaft 14 is provided with a pair of 25 eccentrics 26, 26, which act as one, each having its eccentric rod 27; it being preferable to employ a pair of eccentrics for transmitting the power from shaft 14, though a single eccentric would obviously serve the purpose. 30 The eccentric rods are pivoted at their lower ends to one end of rocker 28 by means of shaft 29, said rocker being journaled at its other end by means of trunnions 30 in a standard 35 supported by base 17. Thus the eccentric rods 27 will impart to rocker 28 a rocking motion which is equal, at the free end thereof (where the rods are attached) to the throw of the eccentrics 26.

40 Rocker 28 transmits the motion received from eccentric rods 27 to another rocking or oscillating member, preferably in the form of a massive bell-crank lever, which has a horizontal arm 33 and a vertical arm 34, and is journaled in the frame at 35.

45 Rocker 28 is bifurcated, its two parallel members being in the same horizontal plane (Fig. 6). The horizontal arm 33 of the bell-crank lever is also bifurcated at its free end (Fig. 8) its two parallel members, 36, 37, 50 being in the same vertical plane; which plane intersects at right angles the plane of rocker 28 occupying a position midway between the two parallel members thereof (Fig. 3). Thus the two members of rocker 28 lie one on one 55 side and the other on the other of the vertical plane of arm 33 of the bell crank lever; while the two members of the latter are one above and the other beneath the horizontal plane of the rocker.

60 The connections between rocker 28 and bell-crank lever 33, 34 are such that, while permitting ready and very precise adjustment of the amount of throw transmitted by the former to the latter while the machine 65 is in operation, the range of adjustment be-

ing from zero to the determined maximum, whatever it may be, they are capable of withstanding for a comparatively long time the deteriorating effects of the rapid and heavy vibrations that pass through them.

The connection between these two members is effected by means of a pivot or trunnion whose support is adjustably carried by one of said members and which is journaled in bearings that are adjustably carried by 70 the other. This feature of the invention is capable of various embodiments. In the preferred construction, which is illustrated in the drawings, arm 33 of the bell-crank is forked at its free end to form two parallel 75 guide-ways 36, 37 (Figs. 1, 7 and 8) one directly above the other, in which is slidably mounted the pivot-carrying block 39 (see enlarged section, Fig. 7). The guide-ways 36, 37 are attached together at their extremities 80 by a strap 40, which helps to impart rigidity 85 to the structure.

The pivot carried by block 39 is in the form of a pair of trunnions 41, each of which is journaled in a bearing block 42, one on each side of sliding block 39. Each of these bearing blocks 42 is slidably mounted in a guide-way 43 in the bifurcated rocker 28 (Figs. 5, 6, 7). Thus the pivoted connection between rocker 28 and bell-crank 33, 34 is 90 movable towards and away from the axis of oscillation of the former. For the purpose of effecting this adjustment readily while the machinery is in operation, a screw 44 is 95 tapped into a threaded perforation which passes through block 39 (Fig. 12). This adjusting screw is operated by hand wheel 45 through worm 46 and worm gear 47 (Figs. 2 and 9). Wheel 45 is provided with a smaller 100 hand wheel 48 for locking it (and the connected adjusting mechanism) in position when not being operated for adjustment of the trunnion-carrying block 39.

105 By reference to Fig. 1, in connection with Figs. 5 and 6, it will be seen that block 39 can be adjusted in one direction until the axis of trunnions 41 carried thereby is in alignment with the axis of oscillation 30 of rocker 28; this being the zero position, in which no motion will be imparted by rocker 28 to bell-crank 33, 34. On the other hand, the farther the pivot-carrying block 39 is moved in the opposite direction, that is towards the free end of rocker 28, the greater will be the amplitude of the vibrations communicated from 110 said rocker to said bell crank, and hence to the shake frame of the paper machine. A scale 50 (Figs. 1 and 8) on guide-way 36 of the bell-crank shows the zero position at the extreme left thereof, and the graduations of the 115 scale indicate increasing degrees of amplitude of the vibrations from left to right. A pointer 51 on block 39 co-acts with said scale to indicate the amplitude of the vibrations that are being imparted to the shake-frame 120 125 130 135 140 145 150 155 160 165 170 175 180 185 190 195 Motion is communicated from arm 34 of the bell-crank to the shake-frame 25 by means of a horizontally reciprocatory rod 53 (Fig. 1) which is detachably connected at 54 with a rod 55 attached to the shake-frame. Said frame, its supporting springs 56, and the table rolls (a part of one of these being indicated at 57) are, or may be, of usual construction, and hence need not be further described.

It will be observed that, in the shake-mechanism described above and illustrated in the accompanying drawings, the power transmitting elements are throughout of solid and rigid construction, and that the connecting elements, while admitting of ready adjustment, and to a nicety, while the machine is running, are so constructed and arranged relatively to the connected parts, as to develop a minimum amount of wear and to sustain a minimum amount of injury by reason of the jars and shocks caused by the rapid and heavy vibrations. This is due partly to the strength and balanced relations of the eccentric rods 27 which transmit motion to rocker 28, and partly to the strength and form of the slideable pivot-carrying block 39 and the slideable bearing blocks 42, which parts have extended bearing surfaces in contact with the surfaces of their respective guide-ways.

Furthermore, the described construction is such as to make it comparatively an easy matter to take up wear at the places where the maximum wear occurs, that is to say, between the contact surfaces of block 39 and its slide-ways and the contact surfaces of the bearing blocks 42 and their slideways. For taking up the wear between block 39 and its slide-ways an adjustable shoe 60 is provided (Fig. 11), in the form of a long and relatively thin plate of gradually increasing thickness, adapted to be inserted between block 39 and its lower guide-ways 37 (Fig. 7). It is provided with threaded sleeves 62 through which pass adjusting bolts 63 whereby it may be fastened in place in threaded sockets in the frame (Figs. 1 and 3) and may be adjusted from time to time to take up the wear.

Similar shoes 65, one of which is shown in detail in Fig. 10, are provided for the bearing blocks 42 (Figs. 1 and 7).

What is claimed is:—

1. A shake mechanism comprising a power shaft, a rocking member pivoted to the frame and receiving a reciprocating motion from said shaft, a vibratory lever, and connecting devices between said rocking member and said lever comprising a pivot and a carrier therefor slideably mounted in ways on one of said members, bearings for said pivot slideably mounted in ways on the other member, and hand operated adjusting means for said movable parts, operable while the machine is running.

2. In a shake mechanism, the combination with a driving shaft, of power transmitting

devices comprising two vibratory members each pivoted to the frame of the machine and one of them connected with said shaft so as to be reciprocated thereby, and an adjustable connection between said members, operable while the machine is running, to vary the amplitude of the vibrations transmitted from one to the other.

3. In a shake mechanism the combination with a driving shaft, of power transmitting devices comprising two vibratory members, eccentrics and eccentric rods connecting one of them with said shaft, and an adjustable connection between said members comprising an adjustable pivot-carrier slidably mounted on one of said members and means operable while the machine is in operation for moving said pivot-carrier towards and away from a position of alinement with the axis of the other vibratory member.

4. In a shake mechanism the combination with the main shaft thereof and with means for driving said shaft at variable speeds, of power transmitting mechanism for converting the rotatory movement of said shaft into vibratory movements of varying amplitude, comprising two pivoted members one of which is connected with said shaft by means of eccentrics and eccentric rods, the latter being connected thereto near its free end, and an adjustable connection between said members operable while the machine is running to vary the amplitude of the vibrations transmitted from one member to the other.

5. In a shake mechanism, the combination with a rotating shaft, of power transmitting devices comprising two vibratory members pivoted to the frame, a pair of eccentrics and eccentric rods for reciprocating one of them, a pivotal connection between said members adjustable to vary the throw of the vibrations imparted from one to the other, and hand operated means for shifting the position of said pivoted connection while the machine is running.

6. In a shake mechanism, the combination with a rotating shaft, of power transmitting devices comprising two vibratory members pivoted to the frame, eccentric means for reciprocating one of said members from said shaft, an adjustable pivotal connection between said members comprising a block slideably mounted on one of them and carrying trunnions journaled in bearing blocks slideably mounted on the other, and adjusting means operable while the machine is running.

7. In a shake mechanism, the combination with a rotating shaft, of power transmitting devices comprising two vibratory members pivoted to the frame, eccentric means for reciprocating one of said members from said shaft, an adjustable pivotal connection between said members comprising a block slid-

ably mounted on one of them and carrying trunnions journaled in bearing blocks slidably mounted on the other, adjustable shoes for taking up wear between the contacting surfaces of said movable parts, and adjusting means operable while the machine is running.

8. In a shake mechanism, the combination with a power shaft, of power transmitting devices comprising a rocker pivoted to the frame, a pair of bearing blocks slidably mounted on said rocker, a pair of eccentrics and eccentric rods for reciprocating said rocker from said shaft, a bell-crank lever also pivoted to the frame and having a bifurcated part embracing said rocker, a block slidably mounted in ways carried by the respective arms of said bifurcated part, trunnions carried by said block and journaled in said bearing blocks, and hand operated means for shifting the position of said trunnion carrier and said bearing blocks relatively to the axis of said rocker.

9. A shake mechanism comprising a power shaft, a vibratory member pivoted to the frame and receiving a reciprocatory motion from said shaft, a second vibratory member, a pivot connection between said vibratory members adjustably mounted upon one of them, and means for adjusting said pivot connection while the shake mechanism is in operation.

10. In a shake mechanism, the combination with a driving shaft, of power transmitting devices comprising two vibratory members each journaled in the frame, one of them being connected with said main shaft so as to be reciprocated thereby, an adjustable pivot connection between said vibratory members, and means operable while the mechanism is in operation for adjusting said pivot connection towards and from a zero position coincident with the axis of oscillation of one of said members.

11. In a shake mechanism the combination with the driving shaft of power transmitting devices comprising two vibratory members each pivoted to the frame, said members being pivoted to one another by means of a connection adjustable towards and away from the axis of oscillation of one of them.

12. A shake mechanism, comprising a power shaft, a vibratory member pivoted to the frame and receiving a reciprocatory motion from said shaft, a second vibratory member, said members being bifurcated and related together so that each has a part that lies in a plane extending between the bifurcations of the other, a pivot connection between said vibratory members adjustably mounted upon one of them, and means for adjusting said pivot connection while the shake mechanism is in operation.

13. The combination with a shake-frame, of a shake mechanism therefor including a

rocker and means for oscillating the same on its axis; driving means connected to the shake-frame; a pivotal connection between said rocker and driving means whereby the former actuates the latter; and means operable to shift the position of said pivotal connection toward and from the axis of oscillation of the rocker, thereby to change the amplitude of movement imparted by the rocker to said driving means.

14. The combination with a shake-frame, of a shake mechanism therefor including a rocker and means for oscillating the same on its axis; driving means connected to the shake-frame; a pivotal connection between said rocker and driving means whereby the former actuates the latter; and means operable while the shake mechanism is in operation to shift the position of said pivotal connection toward and from the axis of oscillation of the rocker, thereby to change the amplitude of movement imparted by the rocker to said driving means.

15. The combination with a shake-frame, of a shake mechanism therefor including a rocker and means for oscillating the same on its axis; driving means connected to the shake-frame, said means including a lever; a pivotal connection between said rocker and said lever whereby the former actuates the latter; and means operable to shift the position of said pivoted connection toward and from the axis of oscillation of said rocker and the fulcrum of said lever, thereby to change the amplitude of movement imparted by the rocker to said driving means.

16. The combination with a shake-frame, of a shake mechanism therefor including a rocker and means for oscillating the same on its axis; driving means connected to the shake-frame, said means including a lever; a pivotal connection between said rocker and said lever whereby the former actuates the latter; and means operable while the shake mechanism is in operation to shift the position of said pivotal connection toward and from the axis of oscillation of said rocker and the fulcrum of said lever, thereby to change the amplitude of movement imparted by the rocker to said driving means.

17. The combination with a shake-frame, of a shake mechanism therefor including a part driven from a source of power; a part connected to said shake-frame; a pivotal connection between said parts; and means operable to shift the position of said pivotal connection, thereby to vary the amplitude of movement imparted to the shake-frame by said shake-mechanism.

18. The combination with a shake-frame, of a shake mechanism therefor including a part driven from a source of power; a part connected to said shake-frame; a pivotal connection between said parts; and means operable to shift the position of said pivotal

connection while the shake mechanism is in operation, thereby to vary the amplitude of movement imparted to the shake-frame by said shake-mechanism.

19. The combination with the shake-frame, of a shake mechanism therefor including in its construction a sliding member adjustable to different positions in a slide-way constituted by two oppositely positioned parallel surfaces, one of said surfaces being that of a plate or shoe the position of which is adjustable to take up wear between the contacting surfaces of the sliding member and slide-way.

15 In testimony whereof I have signed this specification.

FREDERICK A. BOWMAN.
